UNITED STATES PATENT OFFICE.

AUGUST GARTNER, OF RESERVE TOWNSHIP, PENNSYLVANIA.

HOD-ELEVATOR.

SPECIFICATION forming part of Letters Patent No. 717,672, dated January 6, 1903.

Application filed April 5, 1902. Serial No. 101,459. (No model.)

To all whom it may concern:

Be it known that I, AUGUST GARTNER, of Reserve township, in the county of Allegheny and State of Pennsylvania, have invented a certain new and useful Improvement in Hod-Elevators, of which the following is a full, clear, and exact description, reference being had to the accompanying drawings, forming part of this specification, in which—

10 Figure 1 is a front elevation of my improved hod-elevator. Fig. 2 is a side elevation of the same, and Fig. 3 is an end view of the hoisting-drum. Fig. 4 is a view showing a modification.

15 Like symbols of reference indicate like parts wherever they occur.

My invention relates to an improvement in hoisting-elevators for use in the erection of buildings; and it has for its object an elevator 20 which will serve to carry and deliver hods of brick, mortar, or other material rapidly and without waste of time or labor to the story being built and at the same time adapted to be changed and adjusted to different heights or 25 stories without any change of or cutting of the ropes or hoisting-cables and without undue expenditure of time and labor in making such change in height.

To this end it consists of a drum mounted 30 on a suitable frame or foundation at the starting-point or ground-floor, a frame or bearing adapted to support a shaft carrying sheaves or band-wheels, this frame being movable in order to enable it to be carried to suitable supports arranged at various heights or stories, 35 the wheel-supporting shaft being capable of adjustment in the standard, one or more ropes or cables, both ends of which are secured to the circumference of the drum and partially coiled thereon in coils, the loop or standing 40 part of the rope or ropes passing over the sheave on the upper shaft and adapted to be coiled and uncoiled on the drum by the rotation thereof, and hod-supporting cross-bars 45 extending between the standing parts of the ropes, a double-action reversible engine or motor being geared to the hoisting-drum for operating the same, as is hereinafter more fully described.

50 In the drawings, 2 represents the hoisting-drum, which is mounted on suitable bearings 3 on the ground-floor and is provided with a

gear-wheel 4, by means of which it is connected with and adapted to be driven by any suitable double-acting reversible engine or motor. 55 On the circumference of the drum 2 are collars 5, which are secured to the drum by the tightening-bolts 6 and are preferably arranged at the ends of the drum and at points toward the middle. To eyes on these bolts or 60 to other suitable securing devices the two ends of the wire ropes 7 and 8 are made fast, part of the ropes being wound around the circumference of the drum. The standing part of these ropes extends from the coils 9 and 10 to and over the sheaves or wheels 11 and 12, and thence down to the middle collars 5, to which the other ends of the ropes are secured. Instead of two ropes one continuous rope may be employed, it being secured at its middle to the middle collars, 70 as shown at *a* in Fig. 4. The construction otherwise is the same as that illustrated in Figs. 1 and 2. These sheaves 11 and 12 are keyed to the shaft 13, which is journaled in 75 the journal-blocks 14, which journal-blocks are so adjustably mounted in the standards 15 that they may be moved by the adjusting-screws 16 in order to adjust the shaft and sheaves sufficiently to tauten the ropes. The 80 standards 15 are supported by the beams 17, which beams may be the floor-beams of the different stories or beams of scaffolding arranged at any desired height. In order to move the standards 15 upward as the building grows in height, it is only necessary to throw some of the coils of rope from the drum 2, thereby lengthening the standing parts of the ropes, and to place the standards 85 on other supporting-beams at a greater height 90 from the ground.

Extending between and secured to the ropes 7 and 8 are the hod-carrying bars 18 and 19, which serve to support the hods for carrying brick, mortar, or other material. Hooks 95 20 may be fixed to the bars for supporting buckets of water.

The operation of my hod-elevator is as follows: The apparatus having been set in position, the upper standards being at the height 100 to deliver the material at the desired point, the engine or motor is started, causing one end of the ropes to wind and the other end to unwind on the drum 2, thereby carrying the

hod-supporting bar and full hods upward on one side of the drum and the hod-supporting bars and empty hods downward on the other side of the drum. When the full hods are 5 emptied and the empty hods are filled, the engine or motor is reversed and the hods are again carried upward and downward by the winding and unwinding of the ropes 7 and 8 on the drum 2. As the building grows in 10 height the standing parts of the ropes are lengthened in the manner already described.

The advantages of my invention will be apparent to those skilled in the art. The apparatus may be operated by an engine or 15 motor of small size and power, and it can be adjusted to different heights without any cutting or changing of the ropes or cables other than the throwing of a certain number of coils from the drum.

20 What I claim is—

1. In a hod-elevator, the combination of a drum, a frame carrying sheaves, said frame being movable with relation to the drum and drum-supports, ropes, both ends of which are 25 secured to the drum and the standing parts passed over the sheaves, and adapted to wind and unwind on the drum, and hod-carrying

supports secured to the ropes; substantially as specified.

2. In a hod-elevator, the combination of a 30 drum, a frame carrying a shaft, said frame being movable with relation to the drum and drum-supports, sheaves mounted on said shaft, adjusting-screws, ropes, both ends of which are secured to the drum and the standing parts passed over the sheaves, and adapted to wind and unwind on the drum, and hod-carrying supports secured to the ropes; substantially as specified. 35

3. In a hod-elevator, the combination of a 40 drum, a frame carrying sheaves, said frame being movable relatively to the drum and drum-supports, flexible means secured to the drum and passing over said sheaves and adapted to wind and unwind on and from 45 the drum, and hod-carrying supports secured to said flexible means; substantially as described.

In testimony whereof I have hereunto set my hand.

AUGUST GARTNER.
